(57) **CLAIM**

The ornamental design for a backpack as shown and described.

DESCRIPTION

FIG. 1 is a front perspective view of the backpack in a closed configuration;

FIG. 2 is a front view thereof;

FIG. 3 is a right view thereof;

FIG. 4 is a left view thereof;

FIG. 5 is a back view thereof;

FIG. 6 is a top view thereof;

FIG. 7 is a bottom view thereof;

FIG. 8 is a front view of the backpack in an open configuration; and,

FIG. 9 is a left view thereof.

The broken lines depict portions of the backpack that form no part of the design claimed in the instant Application.

1 Claim, 7 Drawing Sheets
